E. P. DU PONT

CARBURETOR

Filed Jan. 10, 1922

FIG. 3.

FIG. 2.

FIG. 1.

INVENTOR

WITNESS:

Robert P. Kitchell.

Eleuthere Paul du Pont

BY

Frank S. Busen
ATTORNEY.

UNITED STATES PATENT OFFICE.

ELEUTHERE PAUL DU PONT, OF MONTCHANIN, DELAWARE.

CARBURETOR.

Application filed January 10, 1922. Serial No. 528,271.

To all whom it may concern:

Be it known that I, ELEUTHERE PAUL DU PONT, a citizen of the United States, residing at Montchanin, county of New Castle, 5 and State of Delaware, have invented a new and useful Improvement in Carburetors, of which the following is a full, clear, and exact description, reference being had to the accompanying drawings, which form a part of 10 this specification.

My invention relates to an improvement in carburetors for internal combustion engines.

It is well known that internal combustion 15 engines are difficult to start in cold weather on the ordinary running mixture for which their carburetors are normally adjusted because of the difficulty of vaporizing gasoline at low temperatures, and this difficulty is 20 most serious in automobile engines which are frequently exposed to extreme cold for long periods.

To obviate this difficulty, it is customary 25 to provide manually operable means for shutting off or choking the air supply of the carburetor, or to supply an increased quantity of gasoline to the mixture, thus providing a rich mixture which will be readily fired in the cylinders at low temperatures 30 and result in an easy starting of the engine.

The rich mixture provided for starting a 35 cold engine is, however, highly injurious to the engine when it is warmed up, since it contains a certain amount of free gasoline, which tends to pass by the pistons and contaminate the lubricating oil and which upon the firing of the mixture tends to deposit carbon. Further, a warmed up motor will 40 not operate efficiently on a rich mixture and fuel is wasted. Therefore, it is essential, in order to avoid inefficiency and damage to the engine, that the carburetor be permitted to deliver a normal mixture as soon as the engine is warmed up.

It is recognized that the drivers of automobiles after having choked their carburetors for starting are prone to forget the choke and operate their engines for long periods on a rich mixture with the result 45 that the engines are damaged as indicated.

The object of my invention is to provide 50 means whereby the carburetor may be manually adjusted to supply a rich mixture for starting and at the same time means which 55 will act automatically to return the carburetor to normal when the engine has reached

a temperature at which it will operate efficiently on the normal mixture which the carburetor is adjusted to supply. Thus, whereas a rich mixture may be supplied at any time 60 for starting a cold engine, the possibility of damage to the engine after it is warmed up, from operating on too rich a mixture, is eliminated.

Having now indicated in a general way 65 the nature, purpose and advantages of my invention, I will proceed to describe a preferred embodiment thereof, with reference to the accompanying drawings, in which—

Fig. 1 is a sectional view of a carburetor 70 embodying my invention.

Figs. 2 and 3 are sectional views of modified details of my invention.

Referring to Figure 1, *a* indicates the float chamber of the carburetor, which is kept supplied with gasoline through pipe *b* leading from a suitable source of supply. *c* is a mixing tube into which leads a feed nozzle *d* in communication with the float chamber through passage *e*. The amount of gasoline fed through the nozzle *d* is controlled by a needle valve *f*. An air inlet *g* communicates with the mixing tube and may be led to a point adjacent the exhaust manifold of an engine to enable a supply of warm air. 85

The mixing tube *c* communicates with a passage *i* adapted to lead the mixture to the engine, which is provided with a butterfly type throttle valve manipulation of which 90 serves to control the speed of the engine.

The carburetor is provided with an auxiliary air valve *j*, adapted to be opened by the suction of the engine, against the action of a spring *k*, as the speed increases, in order to supply additional air to the mixture at increased engine speeds to compensate for the tendency of the air rushing by the small aperture in nozzle *c* to draw an excess of gasoline from the nozzle and supply too rich a mixture. 95

The stem of the valve *f* is slidably passed through the bottom of the carburetor and is threaded at its outer end and screwed through a nut *l*, for adjustment, which in turn is pivotally connected to a lever *m*, which is pivotally supported from the body of the carburetor so that when the lever is moved about its pivot the needle valve will be more or less entered or withdrawn from the feed nozzle *d*. 100

The lever *m* is adapted to be moved downwardly, against the action of a spring *n*, to 105

open the valve *f* by means of a hand lever *o* moving about the suitably notched side of a quadrant *p*, positioned on the instrument board of an automobile, through the medium 5 of a rod *q*, one end of which is pivotally connected to lever *o* while the other end is passed through lever *m*. A stop *r* is adjustably secured to rod *q* above the lever *m*, which when the hand lever *o* is raised will 10 contact with lever *m* and push it downwardly. When the lever *o* is lowered, the stop will be withdrawn from lever *m* and spring *n* will tend to raise the lever to contact with the stop to impart a closing movement of the valve *f*. 15

A lever *s* provided adjacent one end with ratchet teeth *t* is pivotally supported by the carburetor in such a position as to permit the end of lever *m* to engage with the teeth *t*, 20 whereby, when the lever is lowered, as above described, it will be held in the position into which it is moved.

A thermostat *u* is positioned outside of a jacket *v* which is adapted to contain water 25 in circulation with the engine cooling system, which acts to heat the mixing tube and mixture passage of the carburetor. The thermostat is so positioned as to act, when the engine is warmed up, on lever *s* to move 30 it to free the ratchet teeth *t* from the end of lever *m*, permit the spring *n* to raise lever *m* and effect a closing movement of valve *f*.

A hand lever *w*, adapted for movement 35 about a smooth side of quadrant *p*, is connected to one arm of a bell crank lever *y*, pivotally mounted on the carburetor by means of a rod *x*. The other arm of the bell crank lever is adapted, when moved upwardly, to engage with detents *z* in a lever 40 4, pivotally mounted on the carburetor. A spring *5* is secured to the bell crank lever and to the head of valve *j*, which, when the bell crank lever is raised, will be put in tension and retard the opening of valve *j* under 45 the suction set up by the engine and thus retard the admission of auxiliary air.

The lever *s* is connected to the lever 4 by 50 means of a link *6* so that when lever *s* is moved by the thermostat *u* to free the end of lever *m* from teeth *t*, lever *4* will be moved to free the bell crank lever *y* from detents *z* and permit the bell crank lever and hand lever *w* to assume normal position 55 under the influence of spring *5* as it relieves itself of tension.

It will now be observed that in operation, 60 if the needle valve be adjusted to permit the proper amount of gasoline to pass through the nozzle, additional gasoline may be allowed to pass through the nozzle to obtain a rich mixture for starting by adjusting lever *m* downwardly by means of hand lever *w*. The lever *m* will be maintained in such position against the action of spring *n* by the

engagement of its end with teeth *t* on lever *s* and hand lever *o* may be immediately returned to its normal position, thus positioning stop *r* to limit the upward movement of lever *m* when it is released from teeth *t* when the engine is warmed up. 70

The auxiliary air valve is retarded from opening until the engine warms up, thus insuring a rich mixture for starting by means of a spring *5* which is normally out of tension, but which is tensioned by hand lever *w*, adjustment of which rotates the bell crank lever *y* to increase the length of the spring *5* and tension it. The bell crank lever is held in the position in which it is 80 adjusted by engagement with the detents *z* in lever *4*. When the thermostat *u* acts to move lever *s* clear of lever *m*, lever *4*, through its connection with lever *s*, is moved clear of the bell crank and spring *5* relieves itself of tension, enabling valve *j* to be actuated by the engine suction and returning lever *w* to normal position. 85

Referring now to Figures 2, a thermostat *u'* is positioned to operate directly on the stem of an air valve *7*; a jacket *8*, containing water in circulation with the cooling system of the engine, being placed over the thermostat in order to cause it to actuate the valve when the motor is warmed up. Thus 90 in the more simple types of carburetors, in which a mere choking of the air supply will suffice to provide the necessary rich mixture, the adaptation of my invention will be 95 simplified. 100

Referring now to Figure 3, a rod *9* is passed through the instrument board of the automobile and terminates in the button 10 by which the rod may be slid back and forth. On the other end is an eye 11 which 105 may be connected to any device on a carburetor as a choke valve, the purpose of which may be to facilitate starting when cold. A grooved portion 12 of the rod *9* has placed against it a rounded piece 13 held in contact by a spring 14. The piece 13 will tend to drop into the notches or grooves in rod 9 so that the rod will snap into position and will not be jarred out of position by vibration nor will it come out of position without considerable force being applied to it in order to disengage the hold of the piece 13 in notches 12. The position of the rod *9* may be moved or changed at any time irrespective of whether the piece 13 is in contact 110 with it or not. The spring 15 tends to push the rod outward, the tension of the spring 14 being such that the tension of the spring 15 is not sufficient to push the rod unless the tension from the spring 14 is released. This is brought about by the action of the thermostat 16, influenced by heat from the circulation of a portion of the engine cooling water in the space 17, which lifts the piece 13 from the grooves 12, causing a 115 120 125 130

spring 15 to immediately return the rod 9 to its normal position.

Having now fully described my invention, what I claim and desire to protect by Letters 5 Patent is:

1. The combination with a carburetor for internal combustion engines of manually operable means to effect an increase in the opening of the fuel valve of the carburetor 10 from a predetermined adjustment at which the carburetor will function efficiently at efficient engine temperature, and means operable when the engine is at an efficient temperature to automatically effect a return of 15 the fuel valve to its predetermined adjustment.

2. The combination with a carburetor for internal combustion engines, comprising a fuel valve, means to adjust said valve to a predetermined position to supply an efficient amount of fuel, manually operable means whereby said valve may be opened to supply an excess amount of fuel for starting the engine, and means operable automatically 25 under the influence of the heat of the engine adapted to return said valve to its predetermined adjustment after the engine, having been started, has reached an efficient temperature.

3. The combination with a carburetor for internal combustion engines, comprising a fuel valve and an air valve, means to adjust said valves to predetermined relative positions to provide an efficient mixture to the engine, manually operable means whereby the relative adjustment of said valves may be changed to provide an enriched mixture for starting the engine, and means operable automatically under the influence of the heat of the engine adapted to return said valves to their predetermined relative positions after the engine, having been started, has reached an efficient temperature.

4. The combination with a carburetor for internal combustion engines, of an adjustable fuel valve, a pivoted lever supporting said valve, manually operable means for imparting movement to said lever to effect adjustment of said valve out of normal for starting, means to fix said valve in any desired adjustment for starting, and means acting automatically to effect a return of said valve to any desired normal adjustment when the engine after starting has reached 55 an efficient temperature.

5. The combination with a carburetor for internal combustion engines, comprising a fuel valve and an auxiliary air valve, of manually operable means adapted to effect 60 an opening of said fuel valve greater than normal, normally inoperative means adapt-

ed to be manually adjusted to retard the opening of said auxiliary air valve, and means acting automatically to permit said fuel valve to return to normal and render 65 inoperative said retarding means when the engine is at an efficient temperature.

6. The combination with a carburetor for internal combustion engines, comprising an adjustable fuel valve and an auxiliary air valve, of means tending to maintain said fuel valve in normal adjustment, manually operable means adapted to effect a change in the adjustment of said fuel valve, means to maintain said valve in the position to which it is manually adjusted, normally inoperative means adapted to be manually adjusted to retard the opening of said air valve, means tending to maintain said retarding means in adjusted position, and a thermostat adapted to be actuated at an efficient engine temperature to release said fuel valve and permit its return to normal and to render said air valve retarding means inoperative. 75

7. The combination with a carburetor for internal combustion engines, of manually adjustable means for effecting production by the carburetor of a mixture richer than normal for starting, means to maintain said 90 manually adjustable means in adjusted position, means for warming the carburetor, and a thermostat actuatable at an efficient temperature of said warming means to release said maintaining means and permit production by the carburetor of a normal mixture. 95

8. The combination with a carburetor for internal combustion engines, of means to warm the carburetor, means to increase the 100 opening of the gasoline feed thereto, a spring tending to return said feed to normal, a ratchet adapted to maintain said feed at an increased opening, and a thermostat actuatable, when the carburetor is at an efficient temperature, to release said ratchet and permit the feed to return to normal. 105

9. The combination with a carburetor for internal combustion engines, of manually 110 adjustable means for restricting the air admitted to the carburetor, tension means tending to release said restriction, means to hold said restricting means, and a thermostat adapted to be actuated at a predetermined temperature to release said holding means. 115

In testimony of which invention, I have hereunto set my hand, at Wilmington on this second day of December, 1921.

ELEUTHERE PAUL DU PONT.

Witness:

SAMUEL H. BAYNARD, Jr.
